[57] CLAIM

The ornamental design for half-slip, as shown and described.

DESCRIPTION

FIG. 1 is a front elevational view of a half-slip showing my new design;

FIG. 2 is an elevational view of the half-slip as it appears when rotated 30° from the position of FIG. 1; and FIG. 3 is a back elevational view of the half-slip of FIG. 1.

FIG. 2

FIG. 1

U.S. Patent

Nov. 21, 1989

Sheet 2 of 2
